(57) **CLAIM**

The ornamental design for an electric kettle, as shown and described.

DESCRIPTION

1. Electric kettle

1.1 : Perspective

1.2 : Perspective

1.3 : Front

1.4 : Back

1.5 : Left

1.6 : Right

1.7 : Top

1.8 : Bottom

Fig. 1.1 is a top, front and right side perspective view of an electric kettle showing our new design; fig. 1.2 is a bottom, rear and left side perspective view thereof; fig. 1.3 is a front view thereof; fig. 1.4 is a rear view thereof; fig. 1.5 is a left side view thereof; fig. 1.6 is a right side view thereof; fig. 1.7 is a top plan view thereof; fig. 1.8 is a bottom plan view thereof.
